UNITED STATES PATENT OFFICE.

LOUIS HANSON, OF RACINE, WISCONSIN, ASSIGNOR TO OTTO R. BARNETT, OF CHICAGO,
ILLINOIS.

RAIL-STAY.

1,010,423.

Specification of Letters Patent. Patented Dec. 5, 1911.

Application filed April 20, 1911. Serial No. 622,344.

To all whom it may concern:

Be it known that I, Louis HANSON, a citizen of the United States, residing at Racine, in the county of Racine and State of Wisconsin, have invented certain new and useful Improvements in Rail-Stays, of which the following is a specification.

My invention relates to devices known as rail stays, rail anchors, or anti-creepers, and the invention has for its object to provide a rail stay, anchor, or anti-creepers having certain novel and improved features of construction to be hereinafter more fully described.

A primary and specific object of the invention is to provide in a rail stay comprising two parts or elements which are given a relative movement with respect to each other when the device is driven or otherwise caused to grip the rail, means of novel character for locking said parts or elements having said relative movement so as to positively prevent any reverse movement between said parts, thereby preventing the grip of the device on the rail from becoming loosened due to the vibration of the rail or other causes.

The invention is illustrated, in a preferred embodiment, in the accompanying drawing, in which—

Figure 1 is a plan view showing the rail stay applied to a rail; Fig. 2, a sectional elevation taken on line 2—2 of Fig. 1; Figs. 3 and 4, sectional views taken on line 3—3 of Fig. 1, Fig. 4, however, showing the wedge in the position which it takes before it is driven into the clamping position shown in the other figures.

Like characters of reference indicate like parts in the several figures of the drawing.

Referring to the drawing, A represents a T section railway rail of ordinary character and B one of the cross ties on which the rail is laid.

The form of anti-creepers or rail stay in connection with which the features of construction constituting my invention are shown consists of a bar C, preferably of malleable iron, formed at one end with the integral hook or jaw D and at the other end with the integral jaw E and tie abutment F which latter projects from the bar at substantially right angles and is formed with the flange f, the outer surface of which is preferably curved and bears against the edge of tie B; the rail stay comprising fur-

ther a wedge element G which is adapted to be driven into the jaw E, which is preferably tapered in conformity to the taper of the wedge, and against the base of rail A. Preferably the bottom of the jaw E is formed with a recess c in which the wedge is set, and by preference the wedge is formed with a groove g which receives the edge of the rail base. The jaw G is formed with a projection H, the under surface of which is formed with one or more teeth J which are adapted to engage with the oppositely inclined teeth K formed on the upper surface of wedge G. The bar C is preferably strengthened by the strengthening web L which is prolonged so as to extend around the jaw E where its width is preferably increased as indicated at L'. The purpose of this is to give rigidity to the jaw. The projection H is preferably reinforced by a web h which tapers down toward the extremity of the projection. While the jaw E is intended to be as rigid as possible the projection is designed to be capable of slight displacement. For this reason its strengthening rib H is tapered down toward the extremity of the projection which allows the projection to bend slightly.

While malleable iron, of which the device is preferably constructed, does not have a great deal of elasticity, it is possible, with the construction shown, to obtain elasticity enough to carry out the purpose of my invention.

Preferably the projection J dips down a trifle at its extremity so that it stands in the path of the wedge as indicated in Fig. 4. The driving in of the wedge forces the projection up to the position best shown in Fig. 3. If it should happen that the projection, either by faulty casting or subsequent rough handling of the device, be found to stand so far away from the wedge that a close engagement does not take place between the teeth J and K it can easily be hammered down upon the wedge so as to provide such engagement. In fact, if desired, the device could with intention, be constructed so as to operate in this manner. It will be noted that the projection H is so placed that any rough handling that the casting may receive will be likely, if affecting the projection at all, to bend it downwardly or inwardly. This will do no harm because it is forced back by the driving of the wedge.

I am aware that it has been proposed to use co-engaging teeth or serrations for the purpose of locking together the parts of a rail stay, but so far as I am aware the constructions and arrangements which have heretofore been devised are either impractical or very undesirable. It has been proposed, for example, to use a spring tooth in connection with the rack but this is undesirable because a spring element has little strength and at best is very liable to break. Rail stays have also been devised involving the use of interlocking teeth in which the stay is constructed with loose joints so as to allow the teeth to come into engagement. Structures of this sort are undesirable because the loose joints cannot stand the great strains put upon a rail stay and because the looseness of the parts which are in this manner attempted to be locked together militates against the positiveness of the lock. Where the stay comprises two parts which have to be forced or driven into an engaging position by being moved one over the other and which, in order to make the stay effectively grip the tie have to be substantially rigid and eventually assume a close engagement as, for example, where there is a wedge action between the parts, the provision of the surfaces of contact of said parts that are designed to come into the close engagement with coacting teeth defeats and prevents the intimacy of contact between the parts necessary for the effectiveness of the clamp, because, as will be evident, the intermediate positions of the parts while one set of teeth is riding over the other set, will involve a closer contact between the parts than the subsequent positions in which the teeth are engaged. The alternative is that the driving in of the wedge will plane off the teeth and so destroy the intended lock. It will be seen that in the construction herein shown the arrangement of one set of teeth on a slightly flexible projection from one of the rigid co-engaging elements of the stay, to-wit, the jaw E, permits a close engagement between the teeth without affecting the intimacy of contact between the jaw and the wedge which is driven into the jaw. In other words, one set of locking teeth is formed on a part which is not subjected and does not have to be subjected to the clamping strains between the elements forming the stay, and which does not have to be rigid in order to make the clamp of the stay on the rail effective.

While I have shown this device for preventing reverse movement between the parts of a rail stay in connection with a stay consisting of a bar having integral jaws at opposite ends and of a wedge which is driven between the rail base and one of said jaws, it will be obvious that it might be applied

to stays somewhat different in structure and makeup. Furthermore, even with the rail stay of the sort shown the disposition and arrangement of the parts might be varied somewhat without departure from my invention. Therefore I do not limit myself to the particulars shown and described except so far as the same are made specifically limitations on certain of the claims herein.

I have used the word "teeth" to denote the forms designated J and K in the drawing, but it will be understood that the term embraces any sort of serrations or other formations adapted to provide an engagement preventing or resisting the retrograde movement of one part or element of the stay with respect to the other; also that instead of having two sets of teeth as described the lock might be effected by a single tooth working on a succession of teeth.

I claim:

1. A rail stay comprising two elements which together embrace the base of the rail, one of which is adapted to be moved while in close contact with the other into a rigid relationship therewith, and one of which comprises a member adapted to bear against the other element and which is susceptible of slight displacement with respect to the rest of the element of which it forms a part without affecting the rigid engagement between said elements, said member and the portion of the element against which it bears being formed with co-engaging teeth.

2. A rail stay comprising two elements which together embrace the base of the rail, one of which is adapted to be moved while in close contact with the other into rigid relationship therewith, and one of which is formed, integrally therewith, with a member adapted to bear against the other element and which is susceptible of slight displacement with respect to the rest of the element of which it forms a part without affecting the rigid engagement between said elements, said member and the portion of the element against which it bears, being formed with coengaging teeth.

3. A rail stay comprising two elements which together embrace the base of the rail, one of which is adapted to be moved while in close contact with the other into rigid relationship therewith, and one of which is formed with a part which projects from the same in substantial alinement with the surfaces of contact of said elements, which member bears against the other element and is susceptible of slight displacement, said member and the element against which it bears being formed with coengaging teeth.

4. A rail stay comprising two elements which together embrace the base of the rail, adapted to stand in substantially rigid relationship when the rail stay is in normal position on the rail, one of said elements being

- formed with an integral projection which is slightly flexible and which is adapted to bear against the other element, said projection and the element against which it is adapted to bear being formed with coengaging teeth.
5. A rail stay comprising two elements which together embrace the base of the rail adapted to be wedged one against the other, one of said elements being formed with an integral projection which is slightly flexible and which is adapted to bear against the other element, said projection and the element against which it is adapted to bear being formed with co-engaging teeth.
6. A rail stay embracing two elements, one comprising a jaw and the other a wedge adapted to be driven into said jaw, one of said elements being formed with an integral projection which is slightly flexible and which is adapted to bear against the other element, said projection and element against which it is adapted to bear being formed with co-engaging teeth.
7. A rail stay embracing two elements, one comprising a jaw and the other a wedge adapted to be driven into said jaw, said jaw being formed with a projection which bears upon the other element, and said projection and the element on which it bears being formed with coengaging teeth.
8. A rail stay embracing two elements, one comprising a jaw and the other a wedge adapted to be driven into said jaw, one of said elements being formed with an integral projection which is slightly flexible and which is adapted to bear against the other element, said projection and element against which it is directed to bear being formed with coengaging teeth, and a rigidifying web extending around said jaw.
9. A rail stay embracing two elements, one comprising a jaw formed with a rigidifying web and the other a wedge adapted to be driven into said jaw, said jaw being formed with a projection which bears upon the other element, and said projection and the element on which it bears being formed with coengaging teeth.
10. A rail stay embracing two elements, one comprising a jaw formed with a rigidifying web and the other a wedge adapted to be driven into said jaw, said jaw being formed with a projection which bears upon the other element, said projection and the element on which it bears being formed with coengaging teeth, and a tapered strengthening web on said projection.
11. A rail stay comprising a bar provided at each end with a jaw and a wedge adapted to be driven between the rail base and one of said jaws; said last mentioned jaw being formed with a projection having slight flexibility, and said projection and said wedge being formed with coengaging teeth.
12. A rail stay comprising a bar having integral jaws at each end and formed at one end with a tie shutting member which extends at substantially right angles to the bar and is provided with a curved bearing surface, and a wedge formed with a groove to receive the edge of the rail base and adapted to be driven into one of said jaws, said last mentioned jaw being formed with a projection provided with teeth on its under surface and said wedge being provided on its upper surface with teeth adapted to interlock with the teeth on said projection.
